TABLE AND SHELF PROTECTOR

Lyda G. Ebert, Lakewood, Ohio, and Minnie K. Grable, Pittsburgh, Pa.

Application April 9, 1934, Serial No. 719,773

1 Claim. (Cl. 311—103)

The purpose of this invention has been to devise a handy appliance primarily for use in kitchens, consisting of a simple and easily applied and removed protector device for the tops of kitchen tables or the like to which grinding machines are secured when in use. As well known, these grinding machines are employed for the grinding of meat, vegetables, and the like, and are only mounted temporarily on the top of a table or applied temporarily to a sink shelf or the like when they are being used. After use they are removed, cleaned and placed in a suitable storage drawer or compartment.

The clamping means of these grinding machines is such that the clamping arm of the standard of the machine usually engages over the top of a table or similar part and the screw clamping member engages beneath, and the application of the machine and its removal, relative to the table, often mars the top of the table or shelf with which the clamping parts engage. The appliance of this invention is an approximately U-shaped protector made of rubber compound or similar material and capable of being engaged over the edge portion of the table with which a clamp means of a grinding machine will cooperate when the machine is in use, said clamp means receiving therein the protector, and the latter preventing direct engagement of the body clamping parts of the grinding machine standard with the table top or similar part on which the machine is to be mounted.

The invention hereof resides primarily in the specific form of the article of manufacture utilized and includes essentially the formation of the spaced protector pads of the protector device in conjunction with the connecting web therebetween that provides a unique article of manufacture simple to make and cheap for purposes of selling.

An understanding of the invention will be had more readily upon reference to the description hereinafter supplied in conjunction with the annexed drawing, in which—

45 Figure 1 is a top plan view of the protector device of the invention.

Figure 2 is a side view looking toward the outer side of the connecting web between the pads.

Figure 3 is a bottom view of the article.

50 Figure 4 is a transverse sectional view taken on the line 4—4 of Figure 1.

Figure 5 is a sectional view of the article as applied to the edge portion of an ordinary table equipped with a porcelain top.

55 Figure 6 is a perspective view of the reinforce-

ment plate embedded in the lower pad member of the protector.

The article of this invention is exceedingly simple in that it comprises primarily the upper pad or pad member 1, the lower pad or pad member 2, the connecting webs 3 and 4 between said pad members, and the protector plate 5 which is preferably embedded in the pad member 2 in the molding of this pad member.

The pad members 1 and 2 may be of any suitable conformation but it is preferred to make them with rounded end portions to afford a somewhat symmetrical appearance. The inner surfaces of the pad members 1 and 2, that is, the under surface of the member 1 and the upper surface of the member 2, are preferably formed with crossing grooves to slightly roughen the same in respect to the parts which directly engage with the table or other member on which the protector is to be mounted, the said grooves or grooving being indicated at 6 in the drawing.

The plate 5 affords a reinforcement for the lower pad member 2 and this plate may be made of a hard fiber composition or of metal. Since the lower pad member 2 is the one which is engaged by the screw actuated clamp member 7 mounted on the clamping screw 8 of the lower supporting arm 9 of the standard 10 of the grinding machine, see Figure 5, it is desirable that the part 2 have some reinforcement against the impinging or clamping action of the said part 7.

The inner or under portion of the pad member 1 is reduced in thickness a short distance from the free end of said member in order to conform the under-surface somewhat with the shape of the top of an ordinary porcelain covered table, upon which the member 1 will be supported and engaged as it rests beneath the upper portion 11 of the standard of the grinding machine, see Figure 5. Most porcelain-top tables are formed in the manner shown in Figure 5 at 12 and hence the shape of the bearing surface of pad member 1. The webs 3 and 4 are preferably spaced apart a considerable distance and they form flexible connecting elements intermediate the pads 1 and 2. 100 The pad 2 at the inner corner thereof adjoining the lower ends of the webs 3 and 4, is preferably recessed as shown at 2a to conform with the lower portion of the porcelain top 12 adjacent to which this portion of the pad 2 will impinge when it is clamped to the table in the manner shown in Figure 5.

It is believed, in view of the foregoing description, that it is unnecessary to set forth specifically the manner of use of the article of manufacture 110

which has been hereinbefore described. It may be stated, however, that the protector device of the invention is slid on the edge of a table, as illustrated in Figure 5, just prior to engaging the clamping jaws or members of the grinding machine standard with the table, and the protector pads will receive the clamping impingement of the parts 7 and 11 in a self-evident manner and there will be no liability of the upper surface of the table becoming marred, for self-evident reasons, having in view the mode of employment of the article of manufacture. It is contemplated that the protector article of the invention may be made of rubber compound or composition matter of any suitable nature such that the surface with which it engages will be protected against abrasion or marring such as might permanently injure said surface.

It is understood that our device may be used with any machine which requires clamping onto a table or other place where it is used.

Having thus described our invention, what we claim as new and desire to secure by Letters Patent of the United States, is—

As a new article of manufacture, a protector for tables, shelves, or the like of the class described, the same comprising an upper horizontal pad member and a lower horizontal pad member spaced therefrom a distance about equal to the depth of the top of the table to which the article may be applied, vertical connecting webs between the upper and lower horizontal pad members integrally formed therewith, said webs being spaced apart intermediate the ends of the pad members, and each of the webs being spaced from the extremities of the pad members to facilitate the flexing of the pad members relatively to each other in applying the same to a table top or the like for the purpose described, the under-surface of the upper pad member and the upper surface of the lower pad member being roughened by cross-grooving, and a reinforcing plate wholly embedded in the lower pad member between its upper and lower surfaces.
